INFLATABLE BALL

José Hesper, Cordba, Argentina, assignor to John Sheahin, Washington, D. C.

Application February 17, 1936, Serial No. 64,390

1. Claim. (Cl. 273—65)

The present invention relates to new and useful improvements in inflatable balls such as soccer balls, basket-balls or the like, and more particularly to an inflatable ball, the outer peripheral surface of which is entirely free from any projecting portions.

An object of the invention is to provide an inflatable ball wherein the edge portions of the casing adjacent a slit therethrough are laced together for closing the slit in such a manner that the lacing is disposed wholly within the outer peripheral surface of the ball.

A further object of the invention is to provide an inflatable ball of the above type wherein the lacing serves to fix the valve and bladder in a predetermined set position.

A further object of the invention is to provide an inflatable ball of the above type wherein the casing is provided with openings remotely spaced from the slit therethrough so that the edge portions of the casing adjacent the slit may be internally laced together by external manipulation of the lacing.

The above and other objects of the invention will in part be obvious and will be hereinafter more fully described.

In the drawing:

Fig. 1 is a view showing the inflated ball.

Fig. 2 is a fragmentary sectional view of the ball through the slit in the casing.

Fig. 3 is an enlarged bottom view in section of Fig. 2.

Fig. 4 is an enlarged fragmentary view showing the manner in which the bladder and valve are properly located with respect to the casing.

Fig. 5 is a diagrammatic view illustrating the beginning of the stitch formation.

Fig. 6 is a view similar to Fig. 5 showing the completion of the first stitch and the beginning of the succeeding stitch.

Fig. 7 is a sectional view through the end of the closed seam showing the beginning of the final knot formation.

Fig. 8 is a view similar to Fig. 7 showing the final knot.

The invention relates generally to inflatable balls of the type which includes a casing of leather or other wear-resisting material and an inflatable bladder located within the casing. Basket-balls, footballs, soccer balls and hand balls are illustrations of this general type and, while a spherical ball, such as a soccer ball or basket-ball, is shown in Fig. 1 of the accompanying drawing, it is to be clearly understood that the invention is applica-

ble to other types of inflatable balls of this general class.

As shown in Fig. 1 for purposes of illustration, the ball includes a casing or cover 10 consisting of several leather sections 11 which are joined together in any suitable manner. As shown in the accompanying drawing, adjacent pairs of leather sections 11, 11a are left unattached for a short distance so as to afford a slit 12 through which a bladder 13 may be inserted. It is to be understood, of course, that the slit 12 may be placed at any desired location. At one end of the slit 12, the adjacent edges of the casing are cut away to provide an opening 14. The remaining edge portions 15, 16 of the casing adjacent the slit 12 are inturned as shown in Figs. 3, 4, 7 and 8. These inturned portions 15, 16 are provided with spaced apertures 17, 18, 17a and 18a respectively. Remotely spaced from the opposite end of the slit 12, that is, from the end thereof remote from the opening 14, are openings 19, 20 through the sections 11, 11a respectively of the casing.

The bladder 13 is provided with a fabric tongue or flap 21 which is of a general triangular shape and which is adapted to cover the openings 19 and 20 in the casing. The tongue 21 is provided with a recess portion 22 which is adapted to receive the extreme edges of the inturned edge portions 15, 16 when they have been laced together. Secured between the tongue 21 and the body portion of the bladder 13 is a valve 23, preferably of rubber or other resilient material. An opening 24 in the recess portion of the tongue 21 is disposed directly above the valve 23 so as to permit the bladder to be inflated. The details of the valve 23 form no part of the present invention but it includes an integral rubber partition 25 and a fibre disc 26 between which is a lateral opening 27 which communicates with the interior of the bladder. A metal sleeve 31 is disposed around that portion of the valve which includes the flexible partition 25 so as to strengthen the same.

In assembling the ball, the bladder 13 with the tongue 21 and valve 23 attached thereto, are inserted through the slit 12 in the casing 10. The opening 24 in the tongue 21 is positioned in alignment with the opening 14 at the end of the slit 12 so that a pump may be employed for inflating the ball. A sharp-pointed tubular member having a lateral opening therein is adapted to be inserted through the opening 24 in the tongue 21 and thence through the flexible partition 25 in the valve. The pump may be attached to the

free end of the tubular member so as to inflate the bladder. When the tubular member is withdrawn, the inherent resiliency of the partition 25 will close the valve and prevent air from 5 escaping. The wider end of the tongue 21 is disposed toward the opposite end of the slit so that it will be disposed between the bladder 13 and the openings 19, 20 in the sections 11, 11a respectively of the casing 10. The tongue 21 10 will thus prevent any extraneous material from contacting with the bladder and possibly damaging or puncturing the same.

A lacing or cord 28 extends through the tongue 21 and beneath the recessed portion 22 thereof 15 and through the first pair of apertures 17, 18 in the inturned edge portions 15, 16 respectively of the casing and then through the remaining apertures in the edge portions so as to maintain the said edge portions in contact with one another, 20 thus closing the slit 12. The ends of the lacing 28 are knotted beneath the last pair of apertures 17f, 18f in the edge portions noted to maintain the slit closed. When the lacing is thus completed and drawn tight, the tongue 21 will be positioned so that the opening 24 therein is disposed directly below the opening 14 in the casing in order to permit inflation of the bladder 13. It 25 is to be noted that the lacing 28 is disposed wholly within the outer peripheral surface of the casing and that the lacing forms a substantial continuation of the line along which the leather sections 11, 11a are joined, thus affording a substantially invisible seam.

The needle 29 is then passed through the aperture 17 in the edge portion 15 and drawn. The needle 29 is then passed successively through the aperture 18 in the edge portion 16 between the tongue 21 and the casing 10 and out through the opening 20 in the casing. The needle 30 is passed 35 through the aperture 18 in the edge portion 16 and drawn, and then the needle 30 is passed through the aperture 17 in the edge portion 15 between the tongue 21 in the casing 10 and out through the opening 19 in the casing. Thus, it will be seen 40 that the needles 29 and 30 are passed through the edge portions 15 and 16 in opposite directions. The lacing 28 may now be externally manipulated and drawn tight so as to draw the adjacent faces of the edge portions 15 and 16 into contact with 45 one another with the apertures 17 and 18 thereof substantially registering with one another, as shown in Figs. 6 and 7. This tightening of the lacing 28 draws the tongue 21 of the bladder into 50 contact with the casing and definitely locates the opening 24 in the recessed portion of the tongue at a predetermined set position, that is, directly beneath the opening 14 in the casing so that the valve is accessible for inflation or deflation from 55 without the casing.

The needle 29 is now passed back through the opening 20 in the casing between the tongue 21 and the casing and passed through the aperture 18a in the inturned portion 16, and drawn. The needle 29 is then passed through the aperture 17a in the inturned edge portion 15 between the tongue 21 and the casing out through the opening 19 in the casing. The needle 30 is passed back 60 through the opening 19 between the tongue 21 in the casing and through the aperture 17a in the edge portion 15 and drawn. This needle 30 is then passed through the aperture 18a in the edge portion 16 between the tongue and the casing and out through the opening 20 in the casing, as shown 65 in Fig. 6. The lacing 28 may now again be drawn

tight from outside of the casing so as to set the second stitch and cause the faces of the inturned portions 15, 16 to contact with one another and close the slit 12. This same procedure of lacing together the inturned portions 15, 16 is followed in the same manner to the end of the slit 12. 5

In passing the lace or lacing 28 through the last pair of apertures 17f, 18f in the inturned edge portions 15, 16 respectively, the needle 29 is passed into the opening 19 in the casing and successively through the apertures 17f, 18f and out through the opening 20 in the casing. Similarly the needle 30 is passed into the casing through the opening 20 and successively through the apertures 18f, 17f and out through the opening 19 in the casing. This final passage of the needles through the openings in the casing and the last two openings in the inturned edge portions is made possible by the location of the openings 19, 20 which are in substantial alignment with the apertures 17f, 18f in the inturned edge portions 15, 16 respectively. After the lacing 28 is passed through the apertures 17f, 18f in the edge portions, the needle 29 is passed back into the casing through the opening 20 and under the edge portions 15, 16 and then to the outside of the casing through the opening 19 therein so that both needles 29, 30 are now disposed on the same side of the slit. The ends of the lacing 28 are now interlooped, as at A, and the needle 29 is then passed to the inside of the casing through the opening 19 beneath the free edges of the inturned portions 15, 16 and then to the outside of the casing through the opening 20, as shown in Fig. 8. 30 The ends of the lacing 28 may now be pulled so as to tighten the knot or interlocking portion A of the lacing against the edges of the inturned portions 15, 16. This knot formation may be repeated so as to doubly knot the ends of the lacing 35 together within the casing and beneath the edges of the inturned portions 15, 16. The lacing may now be cut off at the openings 19 and 20 so that they will not extend outside of the casing. 40

It is to be clearly understood that various methods of lacing the inturned portions of the casing 45 adjacent the slit therethrough may be employed, so long as the lacing and the knotted end of the lacing are disposed within the casing and wholly beneath the outer peripheral surface thereof so that no projections of any kind will mar the 50 external surface of the ball.

I claim:

An inflatable ball comprising a bladder having a valve for permitting inflation thereof and a 55 valve, a casing having an elongated slit through which the bladder and tongue may be inserted, the edge portions of said casing adjacent said slit being inturned and being cut away at one end of said slit to provide an aperture with which the opening in said tongue is disposed in alignment, and stitching beginning at a point immediately adjacent the aperture in said casing and formed by a lacing passing through said tongue and thereafter through the said inturned edge portions 60 at the point immediately adjacent the cut away portions therein for immediately positioning and holding said valve and said tongue in proper alignment with the aperture in said casing and for drawing said inturned edge portions into contact with one another whereby to close the slit in the casing with the lacing disposed wholly within the outer peripheral surface of the ball. 65
